(57) **CLAIM**

I claim, the ornamental design for a seat, as shown and described.

DESCRIPTION

FIG. 1 is a front perspective view of a seat, showing my new design;

FIG. 2 is a rear perspective view thereof;

FIG. 3 is another front perspective view thereof;

FIG. 4 is a front view thereof;

FIG. 5 is a rear view thereof;

FIG. 6 is a top plan view thereof;

FIG. 7 is a side view thereof taken from the left of FIG. 4; and,

FIG. 8 is an opposite side view thereof taken from the right of FIG. 4.
